ROWLOCK

Herbert J. Gagnon, Flint, Mich.

Application February 19, 1947, Serial No. 729,491

2 Claims. (Cl. 9—26)

1

This invention relates to an improved row lock for an oar and more particularly to a type thereof having a hinged, adjustable ring which may be removably secured to a variety of oar loom sizes.

Persons acquainted with the various types of row locks, especially those used on row boats found on inland lakes, have long been aware of the need for an improved, removable, adjustable row lock which will positively engage the loom of an oar and which will do so without binding at the pivot point between the oar engaging member and the boat engaging member of said row lock.

The conventional wooden oar, now in common use, becomes worn at the point where it is engaged by the row lock regardless of the original fit between said oar and said row lock. Therefore, since those hinged, removable row locks presently in use are not readily adaptable to reductions in shaft diameter, the wear will produce a loose engagement between said oar and said row lock. Such a loose fit is not only irritating in itself, but also accelerates further wearing action.

It is also desirable to have a row lock which could be securely engaged to a conventional tapered oar at a variety of positions along the loom thereof.

Accordingly, it becomes a primary object of this invention to provide an improved, hinged, removable row lock which may be adjustably secured to the loom of an oar.

A further object of this invention is to provide means as aforesaid which is readily adaptable to positive engagement with a variety of sizes of oar loom diameters.

A further object of this invention is to provide means as aforesaid which both can be manufactured quickly and economically, and also can be operated easily by unskilled persons.

Other objects and purposes of this invention will become apparent to persons familiar with this type of equipment upon referring to the accompanying drawings and upon reading the following specification.

In order to meet those objects and purposes heretofore mentioned, as well as others incidental thereto and associated therewith, I have provided an improved row lock which is comprised of a split, hinged ring which engages the loom of an oar, and a tapered swivel pin which engages the gunwale of a boat. The said hinged ring is pivotally supported upon the swivel pin by means of a wing screw, which screw also provides the means by which said hinged ring is adjustably secured to said oar loom.

2

For illustrations of a preferred embodiment of the invention, attention is directed to the accompanying drawings in which:

Figure 1 is an end view of the row lock, to which the invention relates, secured to a portion of an oar loom.

Figure 2 is a side view of the said row lock and a sectional view of the said portion of an oar loom taken along the line II—II in Figure 1.

Figure 3 is a view of the opposite side of the said row lock shown in Figure 2.

The ring 11 of the row lock 10, disclosed herein, is composed of two substantially semi-circular segments 12 and 13 which are pivotally engaged to or hinged upon each other at one end of each thereof by means of a suitable hinge pin 14. The said hinge may be of any convenient conventional type, such as the dove-tail hinge 15 illustrated herewith. That portion of the said ring in the vicinity of the hinge 15 may be appropriately thicker than other portions of the ring, as illustrated in Figure 2, in order to provide a sturdier hinge than would otherwise be possible.

The said semi-circular segments 12 and 13 are provided respectively, with integrally bossed flanges 16 and 17 adjacent to those respective ends 18 and 19, which are remote from the said hinged extremities of the said semi-circular segments. Said bossed flanges 16 and 17 are pivotally associated with the swivel pin head 21 of the swivel pin 20 on opposite sides thereof by means of the winged screw 22.

The said winged screw 22 is rotatably received through a suitable opening 23 in the bossed flange 17 and another suitable opening 24 in the swivel pin head 21, and is threadedly engaged with the said bossed flange 16.

The extensions of the said segments 12 and 13 beyond the flanges 16 and 17 are of such length relative to the corresponding dimension of the swivel head 21 that their respective ends 18 and 19 will engage each other, upon tightening the pin 22, before the flanges 16 and 17 engage opposing sides of the swivel pin head 21. As shown in Figure 2, the row lock is applied to an oar of minimum diameter at the point of application in as much as said ends 18 and 19 are shown in contact with each other. As said row lock is applied to oars of larger diameter, said ends 18 and 19 will be spaced from each other.

The swivel pin 20 has a shank 25 which, as shown herein, is preferably of circular cross-section and tapered for appropriate reception by any conventional type of row lock seat, commonly in use, but not here shown.

The said row lock 10 may be fabricated from

any suitable, durable material such as steel, bronze or magnesium alloy, and may be made in such proportions as to be suited to use on a large life boat or, as illustrated and described herein, for use on a smaller, inland lake row boat.

The inside bore 30 of the said ring 11 may be tapered, as appearing in Figure 1, to conform with the customary taper of a conventional oar loom, or may be a straight bore, as desired. By so tapering the said bore 30, where the row lock is to be used with an oar having a tapered loom, the area of engagement between the inner surface of the said ring and the oar loom is thereby increased thus eliminating any tendency for the oar to wobble in the row lock and the injurious wearing which follows therefrom.

In operation, the winged screw is unscrewed until it disengages the threaded opening in the flange 16 and releases the semi-circular segment 12 of which the said flange 16 is an integral part. The said semi-circular segment 12 may then be swung open about the hinge 15, as illustrated in Figure 3, so as to receive the loom of an oar.

When the oar loom 31 has been received by the inner surface of the semi-circular segment 13, the semi-circular segment 12 is swung back until the inner surface thereof engages the oar loom 31, as illustrated in Figures 1 and 2. The winged screw is threaded into the flange 16 and tightened until the ring 11 is satisfactorily secured to the said oar loom 31.

The said ring 11 and the oar loom supported thereby are thereby free to pivot, by means of the winged screw 22, about the head 21 of the swivel pin 20 whose shank 25 is in turn rotatably supported by means of any conventional, appropriate row lock seat affixed as required to the gunwale of a boat.

Although the above mentioned drawings and description apply to one particular preferred embodiment of the invention, it is not my intentions, implied or otherwise, to eliminate other variations or modifications which do not depart from the scope of the invention unless specifically stated to the contrary in the hereinafter appended claims.

I claim:

1. An adjustable row lock adapted for positive engagement with the loom of an oar, comprising in combination: a first semi-circular segment for partly encircling the said loom of an oar and a second semi-circular segment for substantially but not entirely completing the encircling of said loom, said segments being hingedly connected together at one pair of opposed ends; a pair of bossed flanges, one extending from each segment, near but spaced from the other opposed ends of said segments, one of said flanges having

5 a smooth-bore opening therethrough and the other flange having a threaded opening therethrough coaxial with said smooth-bore opening; a swivel pin of substantially circular cross-section and having a head portion positioned between said flanges, said head having a smooth-bore opening extending therethrough coaxial with the openings in said flanges; a manually rotatable partially threaded screw slidably extending 10 through said smooth bore openings and threadedly received into the said threaded opening of said other bossed flange; said swivel pin head being at least slightly smaller in its dimension parallel to said screw than the combined distances by 15 which the bossed flanges are spaced from the nearest ends of their respective semicircular segments; whereby upon tightening of the said screw the semi-circular segments may securely grip the loom of said oar while permitting the said head of the said swivel pin to pivot freely upon the screw between the said flanges.

2. An adjustable row lock adapted for positive engagement with the loom of an oar, comprising in combination: a first semi-circular segment for partly encircling the said loom of an oar and a second semi-circular segment for substantially but not entirely completing the encircling of said loom, one end of said second segment being hingedly connected to the opposed end of said 25 first segment; a pair of bossed flanges one extending from each of said segments adjacent to but spaced from the ends thereof remote from said hinged ends, one flange having a smooth-bore opening therethrough and the other flange having a threaded opening therethrough coaxial with said smooth-bore opening; a swivel pin having a head portion slidably received 30 between said flanges when said adjacent segment ends are together, said head having a smooth-bore opening extending therethrough coaxial with the openings in said flanges; a manually rotatable screw extending through said smooth bore openings and threadedly received 35 into the said threaded opening of said other bossed flange; whereby upon tightening of the said screw the semi-circular segments are secured upon the loom of an oar while permitting the said head of the said swivel pin to pivot freely upon the screw between the said flanges.

50 HERBERT J. GAGNON.
